CORNER STAY AND STACKING GUIDE

Philip N. Curtis, Worcester, Mass., assignor to
 Baker Box Company, Worcester, Mass., a corporation of Massachusetts

Application December 20, 1937, Serial No. 180,810

7 Claims. (Cl. 217—69)

This invention relates to milk bottle crates and to similar structures which are subject to rough usage and which are commonly stacked one above another, both when in use and when in storage.

It is the general object of my invention to provide an improved construction of corner stay and stacking guide, which may be economically manufactured and which is particularly well adapted to its intended purposes.

A further object of the invention is to provide improved means to protect the upper edges of the crate from wear and also to provide means to reinforce the stacking guide extension, thereby permitting use of lighter metal in the stay member and at the same time providing increased strength.

My invention further relates to arrangements and combinations of parts which will be herein-after described and more particularly pointed out in the appended claims.

Preferred forms of the invention are shown in the drawing, in which

Fig. 1 is a plan view of a corner portion of a crate having my improvements applied thereto;

Fig. 2 is a partial side elevation, looking in the direction of the arrow 2 in Fig. 1;

Fig. 3 is a side elevation of my improved corner stay and stacking guide, partly in section;

Fig. 4 is a plan view, looking in the direction of the arrow 4 in Fig. 3;

Fig. 5 is a partial side elevation of the corner stay with the reenforced bars omitted;

Fig. 6 is a perspective view of one of the re-enforcing bars;

Fig. 7 is a plan view of a double reenforcing member;

Fig. 8 is a view similar to Fig. 1 but showing the double reenforcing member in use; and

Fig. 9 is a perspective view of said double member.

Referring to the drawing, I have shown my invention associated with portions of a crate comprising an end 10 and a side 11 meeting to form a crate corner.

My improved corner stay and stacking guide includes an inner stay member 12 formed of sheet metal and having its lower portion of angular cross section which fits snugly within the corner of the crate.

At its upper end, the stay member 12 is offset inwardly to form a stacking guide 15, adapted to laterally position a second crate mounted thereon. The stay member 12 is also provided with slots 17 through which reenforcing bars 20 are inserted.

Each bar 20 is formed from flat stock and comprises a portion 21 adapted to overlie the upper edge of a crate end 10 or side 11, and a downward extension 22 fitting in a groove 23 in the associated crate side or end. The extensions 22 are enclosed and secured by an outer corner piece 25, preferably secured in position by rivets 26 which extend through the side or end of the crate and which also secure the inner stay member 12 in position.

The upper inner end portions 27 of the bars 20 are preferably wider than the slots 17, to prevent outward displacement of the bars 20, and are shaped to extend upward inside of the stacking guide 15 and to abut and snugly engage the outer side walls thereof, as clearly shown in Figs. 3 and 4.

In the use of stacking guides on bottle crates, it has been found that these guides frequently receive severe transverse blows, which condition has made it necessary to use relatively heavy stock for corner stay members, in order that the stacking guide extensions may be stiff enough to withstand the rough treatment to which they are subjected.

When using my improved reenforcing bars, the portions 27 thereof strongly support the stacking guide extensions and resist lateral displacement thereof. Consequently, lighter sheet metal may be used for the corner stay members, while at the same time the stacking guide is reinforced and is actually stronger than in the previous construction in which heavier metal was used.

Furthermore, the portions 21 overlying the upper edges of the crate resist wear on the wood parts, and the downward extensions 22 secured by the corner piece 25 firmly resist inward displacement of the reenforcing bars 20. These re-enforcing bars, being relatively small, may be made of heavier stock, so that any desired reinforcement may be provided.

In Figs. 7 to 9, I have shown a double reenforcing member 30 so shaped that, when bent to the form indicated in Fig. 9, the connecting portion 31 will form a right angle and the offset portions 32 and depending portions 33 will all be parallel. These parallel parts 31 and 32 may be inserted through a pair of slots in the corner stay member as previously described, it being merely necessary to make the slots a little deeper to accommodate the angle between the parts 32 and 33. The connecting portion 31, being unitary and bent to a right angle as shown in Figs. 8 and 9, even more effectively reinforces the stacking guide extension 15^a.

Having thus described my invention and the advantages thereof, I do not wish to be limited to the details herein disclosed, otherwise than as set forth in the claims, but what I claim is:

1. In a bottle crate, a corner reenforcement comprising a vertically disposed outer corner piece engaging the outer vertical surfaces of said crate at both sides of a corner edge, a vertically disposed inner stay member of angular cross section secured in a vertical inner corner of said crate and engaging the inner vertical surfaces of said crate at both sides of said corner angle and inwardly opposite said outer corner piece and having a stacking guide extension at its upper end and slots in its side walls near said upper end, and additional reenforcing means seated in said slots and having portions secured outside said crate and between said crate and said outer corner piece, the upper end portions of said reenforcing means extending upward inside the stacking guide extension of said inner stay member and abutting and supporting said extension against inward lateral displacement.

2. In a bottle crate, a corner reenforcement comprising a vertically disposed outer corner piece engaging the outer vertical surfaces of said crate at both sides of a corner edge, a vertically disposed inner stay member of angular cross section secured in a vertical inner corner of said crate and engaging the inner vertical surfaces of said crate at both sides of said corner angle and inwardly opposite said outer corner piece and having a stacking guide extension at its upper end and slots in its side walls near said upper end, additional reenforcing means seated in said slots and having portions lying across the upper edges of said crate, with downward extensions seated in grooves in the outer surfaces of said crate side and end, and within said outer corner piece and means to secure said extensions in said grooves, and the upper end portions of said reenforcing means extending upward inside the stacking guide extension of said inner stay member and abutting and supporting said extension against inward lateral displacement.

3. In a bottle crate, a corner reenforcement comprising a vertically disposed inner corner stay member of angular cross section secured in a vertical inner corner of said crate and engaging the inner vertical surfaces of said crate at both sides of said corner angle and having a stacking guide extension at its upper end and slots in its side walls near said upper end, and a pair of reenforcing bars additional to said stay member and each extending outward through one of said slots and secured outside said crate, the inner ends of said bars extending upward inside of the stacking guide of said inner stay member extension and reenforcing said extension against inward lateral displacement.

4. In a bottle crate, a corner reenforcement comprising a vertically disposed inner corner stay member of angular cross section secured in a vertical inner corner of said crate and engaging the inner vertical surfaces of said crate at both sides of said corner angle and having a

stacking guide extension at its upper end and slots in its side walls near said upper end, a pair of reenforcing bars additional to said stay member and each extending outward through one of said slots and having a portion overlying an upper edge of said crate and having a downward extension of said portion outside said crate, and means to hold said bars in reenforcing position, the inner upper ends of said bars fitting and abutting the inside of the stacking guide of said inner stay member extension and supporting said extension against inward lateral displacement.

5. In a bottle crate, a corner reenforcement comprising a vertically disposed inner corner stay member of angular cross section secured in a vertical inner corner of said crate and engaging the inner vertical surfaces of said crate at both sides of said corner angle and having a stacking guide extension at its upper end and slots in its side walls near said upper end, and an additional double reenforcing member having two integral leg portions each insertable through one of said slots and secured outside said crate, and said reenforcing member having an inner connecting portion extended upward inside of the stacking guide of said inner stay member extension and supporting said extension against inward lateral displacement.

6. In a bottle crate, a corner reenforcement comprising a vertically disposed inner corner stay member of angular cross section secured in a vertical inner corner of said crate and engaging the inner vertical surfaces of said crate at both sides of said corner angle and having a stacking guide extension at its upper end and slots in its side walls near said upper end, and an additional double reenforcing member having two integral leg portions each insertable through one of said slots and secured outside said crate, and said reenforcing member having an inner connecting portion bent to a right angle and extended upward inside of the stacking guide of said inner stay member extension and supporting said extension against inward lateral displacement.

7. In a bottle crate, a corner reenforcement comprising a vertically disposed inner corner stay member of angular cross section secured in a vertical inner corner of said crate and engaging the inner vertical surfaces of said crate at both sides of said corner angle and having a stacking guide extension at its upper end and slots in its side walls near said upper end, and an additional double reenforcing member made from a flat blank and having two integral leg portions each insertable through one of said slots and bent downward and secured outside said crate, said leg portions being parallel in the blank and also in secured position, and said reenforcing member having an inner connecting portion bent to a right angle and extended upward inside of the stacking guide of said inner stay member extension and supporting said extension against inward lateral displacement.

PHILIP N. CURTIS.
